SKI BINDING

Jakob Eigenheer, Zurich, Switzerland, assignor to
 Belmag Zurich, Beleuchtungs-Und Metallin-
 dustrie A.-G., Zurich, Switzerland

Application June 7, 1939, Serial No. 277,897
 In Switzerland July 15, 1938

3 Claims. (Cl. 280—11.35)

The subject of the present invention is a ski-binding and more particularly a front pull binding, wherein a stretcher for the heel pull member is pivotally mounted in front of the toe cheeks on the back of the ski.

The binding according to the invention permits of a rapid adjustment of the heel loop and of the pull exerted thereby on the shoe.

The accompanying drawing shows a preferred form of construction of the subject of the invention, wherein:

Fig. 1 shows a side elevation of the binding together with a portion of the ski.

Fig. 2 is a plan of Fig. 1.

Fig. 3 is a side elevation, and

Fig. 4 is a plan to a larger scale.

Figs. 5, 6 and 7 are sections on the lines V—V, VI—VI, VII—VII of Figs. 3 and 4.

In the form of construction of the ski binding shown in the drawing there is provided as the heel pull member a cable 1 to which there is applied at the heel portion a rubber tubing 2 which serves to guide the cable around the heel.

The binding is provided with toe plates, known per se, of which the vertical portion is provided with supports 4 for the cable so that this can be selectively engaged with one of the supports 4 or can be passed below the horizontal toe plate portion 3. Over the cables there is provided in the known manner a cable protecting spirally wound wire. In front of the toe irons there is located a stretcher 5 which is pivoted about a bolt 6 of the guide member 7. The guide member 7 is guided in the notched plate 8 of which the cross-sectional shape will appear from Figs. 6 and 7. The guide member is provided with a T-shaped bar 9, of which the flanges 10 are engaged by guide bars 11 of the notched plate 8. In this manner the movement of the guide member in the notched plate 8 is rendered possible.

In the guide member 7 a catch 12 is mounted for vertical movement in that it passes by means of a bolt 13 through a slot 14 of the bar 9 of the guide member 7. Lugs 15 facilitate the engagement of the catch 12 and a lifting and lowering thereof. The bars 11, as shown in Figs. 3 and 4 are provided with notches 16 with which the lower end of the catch 12 can engage. When the catch has engaged with one of the notches 16 the guide member 7 is no longer movable in the longitudinal direction.

The connection of the cable 1 to the stretcher 5 is effected through tension springs 17 formed of spirally wound wire of suitable thickness. The front ends of the tension springs 17 are hingedly

connected by a bolt 18 to the stretcher 5. The rear ends are spaced apart at the correct distance by a strap 19 so that the rear ends of the springs are further apart than the front ends of the springs so that a gradual passage of the cable 5 under the toe irons 3 is possible without it being necessary to effect for this purpose a sudden tension, and consequently incur the liability of fracture.

The connection of the cable 1 to the springs 17 or to the strap 19 is effected by means of screws 20 which are movable on the cable, for example on the cable closing sleeve, and engage with internally screw-threaded sleeves 21. These sleeves 21 are held immovable in the springs 17 or in the strap 19. Against the front end of the hollow screw 20 there bears the cable end member 22 which is pressed upon the actual cable. By adjusting the screws 20 it is also possible to effect an additional variation of the width of the heel 20 pull loop, similar variation being also possible by the notches 16 and catch 12 and also by the construction of the guide member 7 and of the stretcher 5 to be described hereinafter.

The guide member 7, as shown in Fig. 5, is provided with an N-shaped slot 23 in which there is guided the bolt 6. According to whether the bolt 6 is engaged in the front or rear limb of the slot 23, the width of the cable loop can be modified.

The stretcher itself, as in the form of construction according to the drawing, may be formed as an extrusion casting. It may however also be bent from sheet steel, whereby it provides for greater strength.

What I claim is:

1. Ski binding comprising a cable as a heel pull member, a cable protecting sheath enclosing said cable, cable end members rigidly secured to the two ends of said cable, toe irons adapted to be secured to the ski, a stretcher lever located in front of the toe irons, a pair of tension springs hinged to said stretcher lever and operatively connected with said cable end members, a notched plate adapted to be secured to the back of the ski, a guide member adjustably guided in said plate, said stretcher lever adjustably engaging said guide member.

2. Ski binding comprising a cable as a heel pull member, a cable protecting sheath enclosing said cable, cable end members rigidly secured to the two ends of said cable, toe irons adapted to be secured to the ski, a stretcher lever located in front of the toe irons, a pair of tension springs hinged to said stretcher lever and operatively con-

- nected with said cable end members, a notched plate adapted to be secured to the back of the ski, a guide member adjustably guided in said plate, said stretcher lever adjustably engaging
5 said guide member, and means for locking the guide member relatively to the notched plate, said means including a catch mounted for vertical movement on the guide member and engaging with the notches of the notched plate.
- 10 3. Ski binding comprising a cable as a heel pull member, a cable protecting sheath enclosing said cable, cable end members rigidly secured to the two ends of said cable, toe irons adapted to be secured to the ski, a stretcher lever located in
15 front of the toe irons, a pair of tension springs

hinged at one end of each to said stretcher lever and operatively connected with said cable end members, a notched plate adapted to be secured to the back of the ski, a guide member adjustably guided in said plate, said stretcher lever adjustably engaging said guide member, a strap operatively connecting together the other ends of the tension springs, and means for adjustably connecting the ends of the cable to said springs, said means including internally screw threaded sleeves 5
10 screwing into the ends of said springs and screws on said cable adjacent said cable end members and screwing into said internally screw threaded sleeves.

JAKOB EIGENHEER. 15
